UNITED STATES PATENT OFFICE

2,006,759

HOT-BED

Louis C. Edgar, Swissvale, Pa.

Application March 2, 1933, Serial No. 659,387

3 Claims. (Cl. 80—42)

This invention relates to hot-beds such as are used in steel mills for cooling work which has just been rolled, one of the objects being the provision of smooth carrying surfaces. Another object is 5 to construct these hot-beds so the skids forming their carrying surfaces are free to expand when heated, without including pivoting or sliding surfaces which naturally tend to reduce the desired stability of such structures. Other objects may 10 later become apparent.

The accompanying drawing illustrates one example of the invention, the various figures being as follows:

Figure 1 a perspective;

15 Figure 2 a transverse cross-section from the central supports shown in Figure 1; and

Figure 3 another transverse cross-section taken from one of the other supports shown in Figure 1.

A hot-bed's carrying surface is generally a plurality of parallel skids. The size of most beds requires that these be made from sections, which are frequently railroad rails. The ends of these rails are generally not abutted because of the difficulty heretofore experienced in mounting 20 them to provide for the thusly exaggerated elongation caused by heat expansion. Ordinarily, their ends are overlapped and require frequent adjustment to keep them respectively flush.

The drawing shows the skids A as including 30 abutting rail sections 1 and 2 whose ends are interfastened by bolted side plates 3, which are angle members and are themselves bolted to anchorages 4. Their top edges are carefully machined to insure flushness with the heads of the 35 rails. The anchorages 4 are in turn bolted to a suitable base 5.

The skids may consist of as many rail sections as proves necessary to secure the desired size. Of course, more simplified connections between the 40 rails may be made at unanchored points, provided they are sufficiently rigid and do not obstruct the passage of work.

One or more flexible supports B are on both 45 sides of the anchorages 4. These each include downwardly spreading parts 6 provided with flexible plates 7 and 8 at their top and bottom ends, which are respectively connected to the skids being supported and to a supporting base.

The spreading parts 6 are angle irons riveted 50 to both sides of the plates 7 and 8 which are themselves connected by other similarly riveted angle irons to the parts mentioned.

It is to be noted that the plates 7 and 8 are 55 arranged at right angles to the center line of the supporting skids and are therefore flexible to lon-

gitudinal and rigid to lateral movements of the latter. Further, that the skids A are not associated with any structure which might prevent them from flexing the slight amount obviously required to accommodate the swinging actions of the flexible supports B. That is, if the skids were carried by heavy relatively rigid beams or the like which were, in turn, mounted by the flexible supports, the entire structure would be relatively rigid and would probably warp during 10 use. Such warping might also happen if the skids were not each supplied with its own individual supports in the manner illustrated, but were, instead, provided with flexible supports 15 common to all or a plurality of the skids.

Although a specific example of this invention is disclosed in accordance with the patent statutes, it is not intended to limit the inventive features exactly thereto, except as defined by the following claims.

I claim:

1. A hot-bed including the combination of a plurality of skids, an anchorage for each of said skids and one or more supports for each of said skids, said supports each including downwardly spreading parts provided with flexible plates at their top and bottom ends, which are respectively immovably connected to a supported skid at substantially right angles thereto and to a supporting base, said parts and said plates being in substantially the same plane.

2. A hot-bed including the combination of a plurality of parallel skids, a centrally arranged anchorage for each of said skids, and a plurality of supports for said skids spaced on both sides of said anchorages and each including downwardly spreading parts provided with flexible plates at their top and bottom ends, which are respectively immovably connected to a supported skid at right angles to the center line thereof and to a supporting base, said parts and said plates being in substantially the same plane.

3. A hot-bed including a plurality of skids that are arranged in parallel relationship, each of said skids including at least two aligned rails with their respective ends immovably interconnected, said skids being positioned by supports which are immovably fixed to the same and are immovably anchored, at least a portion of said supports including interposed flexible plates that immovably connect therewith and are arranged to flex to accommodate expansion and contraction of said skids.

LOUIS C. EDGAR. 55
